DESIGN FOR A POCKET COMB

Seth T. Nussbaum, Indianapolis, Ind.

Application December 18, 1943, Serial No. 112,029

Term of patent 7 years

To all whom it may concern:

Be it known that I, Seth T. Nussbaum, a citizen of the United States and a resident of Indianapolis, county of Marion, and State of Indiana, have invented a new, original, and ornamental Design for a Pocket Comb, of which the following is a specification, reference being had to the accompanying drawing, forming a part thereof.

In the drawing Fig. 1 is a front elevational view of a pocket comb, showing my new design.

Fig. 2 is a top plan view thereof.

I claim:

The ornamental design for a pocket comb, as shown.

SETH T. NUSSBAUM.
